ABRADING MACHINE

Joseph Gouldbourn and William Roderick Barclay, Leicester, England, assignors to United Shoe Machinery Corporation, Paterson, N. J., a corporation of New Jersey

Application August 3, 1932, Serial No. 627,330

In Great Britain August 25, 1931

5 Claims. (Cl. 51—135)

This invention relates to abrading machines and is herein illustrated as embodied in a machine for scouring the breast surfaces of unattached heels.

In the manufacture of many types of shoes it is a common practice to scour the breast surface of the heel before attaching it to the shoe. In order to obtain a smooth, well finished surface the scouring operation is usually performed in two stages, a relatively coarse abrasive being used in the first stage and a relatively fine abrasive being used in the second stage. A pair of horizontally disposed scouring rolls having coarse and fine abrasives respectively are ordinarily used for this purpose. While the time required for transferring a heel from the coarse roll to the fine roll appears to be small, nevertheless it represents an appreciable fraction of the time required to perform the entire scouring operation and the total amount of time thus lost in the course of a day is considerable.

It is an object of the present invention to provide a machine having both coarse and fine abrading members so constructed and arranged as to enable a work-piece to be transferred from the coarse to the fine abrading member with substantially no loss of time. The illustrated machine is provided with a plurality of driven abrading elements of different degrees of coarseness and fineness respectively and a work-rest so mounted as to be yieldable upon pressure to enable it to be shifted from a position convenient for the presentation of work to one abrading element to a position convenient for the presentation of the work to another abrading element. In accordance with a feature of the invention, the abrading elements are arranged in side-by-side relation upon a driven roll and the work rest is guided for movement in a path

which is substantially parallel to the axis of the roll, the work rest being normally maintained in a position convenient for the presentation of work to a relatively coarse abrading element. As illustrated, a stop is employed which determines the normal position of the work rest and is adjacent to the relatively coarse abrading element, and a spring normally maintains the work rest against this stop.

In accordance with a further feature of the invention the illustrated abrading members are arranged with their abrading surfaces disposed vertically with the relatively coarse abrading members above the relatively finer abrading members. An advantage of this arrangement resides

first to subject the work to the upper abrading member which is relatively coarse and then merely by the downward pressure of his hand to shift the work to the lower abrading member which is relatively fine. These and other features of the invention including certain details of construction and combinations of parts will be more fully explained in the accompanying description to be read in connection with the accompanying drawings in which

Fig. 1 is a front elevation of the illustrated machine;

Fig. 2 is a right-hand side elevation of the machine;

Fig. 3 is a plan view of the machine with the cover removed showing the scouring belts; and

Fig. 4 is a front elevation of the mechanism which carries the scouring belts.

The said illustrative machine comprises a hollow column 1 carrying a head casting 3. In suitable bearings 5 is journalled a vertical shaft 7 on the lower end of which are mounted two pulleys 9 and 11. Journalled in suitable bearings 12 near the base of the column 1 is a horizontal shaft 13. On the left hand end portion of the shaft 13 are mounted fast and loose pulleys 15 and 17. A belt shifter 19 is provided. This is carried on a bar 21 slidably mounted in the base of the column 1. A handle 23 is pivoted at 25 to the front of the column 1 and is operatively connected to the bar 21. Movement of the handle 23 causes sliding movement of the bar 21 and so causes displacement of the belt shifter. A belt from an external source of power serves to drive the shaft 13 when it passes round the fast pulley 15. Near the middle of the shaft 13 there is mounted on it a pulley 27. A belt 29 passes round this pulley 27 and also round one or the other of the pulleys 9, 11 already mentioned. The pulleys 9 and 11 are of different diameters in order that for a reason hereinafter to be explained the shaft 13 may be driven at different speeds. In order that the belt 29 may be maintained tight notwithstanding the difference in diameter between the pulleys 9 and 11, the belt is also led round two pulleys 31, 33 the positions of which may be adjusted. These latter pulleys are mounted as follows. Secured by a bolt 35 to the column 1 is a bracket 37 in which is an arcuate slot 39. In this slot is adjustably fixed, by means of a nut provided with a locking handle 41, a stud 43 on which the pulley 33 is carried. Also mounted on the stud 43 is a lever 45 at the rear end of which is carried the pulley 31 and the front end of which

is pivotally connected to one arm 47 of a bell crank lever pivoted at 48 to the column 1. Another arm 51 of the bell crank lever is formed as a handle. The paths of movement of the stud 43 in the slot 39 and of the pivotal connection between the lever 45 and the arm 47 are substantially alike in respect to curvature and direction, so as to provide for a substantially parallel movement of the lever 45. Upon loosening the locking lever 46 and manipulating the handle 51 the pulleys 31 and 33 may be shifted from the position shown in Fig. 2, wherein the belt 29 drives the pulley 9, to a position wherein the belt 29 drives the pulley 11, and in a similar manner the pulleys 15 31 and 33 may be shifted back again to enable the belt 29 to drive the pulley 9, the arrangement being such that the belt 29 will be under tension for either pulley. In order to facilitate shifting the pulleys 31 and 33, the tension of the belt 29 20 is allowed to slacken. This is accomplished by means of a short slot 46 in the lever 45, which slot enables the lever 45 to move toward the left under the tension of the belt 29 upon loosening of the locking lever 46. Before locking the lever 45 25 in either of its positions of adjustment, it is again moved to the right to tension the belt 29.

Carried on the upper end portion of the shaft 7 is an abrasive band carrying roll 53. The main portion of the roll 53 is of wood but the roll is 30 axially bored to receive a metal sleeve 55 through which the roll is mounted on the shaft 7. The external surface of the roll 53 is covered by a felt sleeve 57. A fixed collar 59 is provided on the shaft 7 upon which the roll 53 rests, the roll being suitably recessed at 61 to receive the collar. The upper end of the shaft 7 is reduced and screw 35 threaded so that the roll 53 may be secured to the shaft by means of a nut 63. The roll is suitably recessed at 65 to receive the nut 63.

40 Running over the surface of the roll 53 are a rough abrasive band 67 and a fine abrasive band 69, the rough band being above the fine band. The bands 67 and 69 are endless belts having their respective operating surfaces coated with 45 abrasive material. Upon a vertical shaft 71 (Fig. 4) fixedly mounted in the head casting 3 are mounted two members 73 and 75 which serve respectively to support pulleys 77 and 79 round which pulleys respectively run the bands 67 and 69. Separate adjusting means are provided for 50 altering the position or angular aspect of the pulleys 77 and 79 in accordance with variations in the lengths of scouring bands. As this means is similar in the case of both pulleys it need only be described with reference to one. The pulley 79 for example is carried on a short vertical shaft 81 carried by a member 83 pivoted by means of a pin 85 to an arm 87 extending from the member 75. The member 83 is provided with a rearwardly 55 extending arm 89 and located below the end of this arm is a headed stud 91 carried by an arm 93 extending from the member 75. A rod 95 passes through the end portion of the arm 89 and through the head of the stud 91 and is in screw threaded relation with both these parts. The 60 portion of the rod passing through the arm 89 is however screw threaded in the opposite direction to that passing through the stud 91 so that on rotating the rod 95 (which is provided at its top end with a knurled head 97) the arm 89 is displaced relatively to the stud 91. This causes the member 83 to be turned about the stud 85 and so cause slight variation in the angular aspect 65 of the pulley 79 in relation to the roll 53. It is found that it is convenient to provide such an

adjustment as on turning the rod 95 the position of the band 69 on the surface of the roll 53 may be accurately adjusted. By means of this adjustment the abrasive bands 67 and 69 may be brought as close together on the roll 53 as may be desirable, allowing for reasonable clearance, regardless of variations in the width of the abrasive bands. The member 75 has also formed upon it a forwardly projecting lug 99 to which is pivoted one end of a rod 101. The head casting 3 is 10 provided with an upwardly extending wall 103 which serves to enclose the scouring bands. This wall has an aperture therein through which the rod 101 passes and has also a lug 105 formed upon it. In this lug is a vertical hole in which is received a short stud 107, flattened at one side. The stud 107 has a horizontal bore made therein through which the rod 101 passes. At its end the rod 101 has a nut 109 and a lock nut 111 in threaded relation therewith. The arrangement 15 is obviously such that should the band 69 be too slack the nut 109 can be tightened. This will swing the member 75 anti-clockwise (as seen in Figure 3) about the shaft 71 and so serve to 20 tighten the band.

25 The work supporting means with which the machine is provided comprises a table or work rest 113. This table has two downwardly extending lugs 115 by which it is pivoted about a horizontal axis to a support 117. The arrangement is such 30 that the table may be tilted to a desired angular position and then fixed in such position by tightening a lock nut 119 which has an extension handle 121. The support 117 can be moved forwardly or rearwardly in a dovetailed slide 123 in 35 a block 125. A set screw 127 is provided whereby the support 117 may be locked in adjusted position relatively to the block 125. The block 125 is carried on two supporting columns 129, 131 40 which pass slidably through holes in a bracket member 133 which projects forwardly from the head casting 3. Threaded into the lower end of the column 129 and in axial relation thereto is a screw 135 to which is pinned a sleeve 137. A member 139 is clamped to the column 131 and surrounds the sleeve 137. A leather washer 141 45 is arranged between the top surface of the member 139 and the bottom surface of the forwardly projecting portion of the head casting 3 through which the column 129 passes. Two tension 50 springs 143 are arranged between pins 145 and 147 respectively on the bracket member 133 and the member 139. These springs 143 normally serve to hold the table 113 in raised position and it will be appreciated that the level of this raised position in which the table is normally held may be 55 adjusted by unclamping the member 139 from the column 131 and by rotating a head 149 with which the screw 135 is provided, after which the member 139 may again be clamped securely to the 60 column 131.

65 The machine is furnished with dust collecting means. As already mentioned the head casting 3 has formed on it a vertical wall 103 which serves to enclose the scouring bands. At the top of the wall 103 is mounted a detachable cover 151. As will be mentioned later, it may be desirable when operating upon different classes of work to make use of rolls 53 of different diameter. In order 70 that the dust collecting means may be equally effective when rolls of different diameters are employed a shutter 153 is secured by means of screws 155 to the wall 103 adjacent the left hand side of the roll 53 while the mouth of a swingable duct 157 lies adjacent the right hand side of the 75

roll. If a roll 53 of for example smaller diameter be substituted for the one already in place, the screws 155 can be loosened and the shutter moved so that its edge is brought up adjacent to the surface of the new roll while the end of the duct 157 can be swung up to the surface of the new roll. A clearance is cut in the wall 163 to allow of movement of the front end of the duct 151, and a slidable shutter 159 is provided to close up 5 as much as possible of the aperture between the wall and duct. The duct 157 is connected by a pipe 161 with a fan 163 while another duct (the mouth of which is shown in Figure 3 at 165) leads also to the fan 163 from the chamber which is 10 constituted by the head casting 3, the walls 163 of the casting 3, and the cover 161. The fan 163 is driven by means of a belt 167 which passes round a pulley 169 on the shaft 16.

The operation of scouring the breast surface 20 of a loose heel by means of the illustrative machine will now be briefly described. In the case of heels of different styles it may be desired to scour their breast surfaces to different curvatures and accordingly rolls 53 of different diameter 25 may be provided which are readily mounted upon or taken off from the shaft 7. For example the machine may have three alternative rolls respectively 8, 5 and 4 inches in diameter. When a large diameter roll is in place on the machine the belt 29 will be arranged to pass round the pulley 9 on the shaft 7 but when the larger roll is replaced by a smaller one it will be desirable to change the belt 29 over to the small pulley 11. Thus the linear speed of the abrasive bands 67 30 and 69 which pass round the roll may be kept substantially constant despite the employment of rolls of different diameters.

A loose heel to be scoured will usually previously have been breasted (for example by the common guillotine knife type of heel breasting machine). The inclination of the general plane of the heel breast to the vertical will vary somewhat with different styles of heels and allowance can be made for this in the illustrative machine by 40 loosening the nut 119 by means of the extension handle 121 and thereafter adjusting the angularity of the table 113. The position of the table will also be adjusted along the slide 123 in accordance with the diameter of the particular roll 50 53 in use. The heel to be scoured is placed upon the table 113 by the operator, with the attaching face of the heel extending downwardly and with its breast towards the scouring bands. As the marginal portion of the attaching face towards 55 the breast of the heel is usually curved, a suitable curved member 171 is conveniently attached to the rear portion of the table 113 in order that a heel may be supported more stably upon the table. As has been hereinbefore mentioned the table is 60 normally held in raised position by the action of the springs 143. When the table is in this position the breast surface of a heel positioned as just described upon the table will be on a level with the upper (or rough) abrasive band 67. The operator presses the heel, still positioned on the table, against the band 67 until he considers that it has been scoured to a sufficient extent by the rough abrasive paper when he will press the heel (and table) downwardly against the action of the 65 springs 143. The breast surface of the heel will thus pass down to the lower (or fine) abrasive band 69 and its scouring will be finished thereby. When the operator removes the heel the table will of course rise automatically to be ready to 70 receive the next heel to be scoured. It will be

realized that the arrangement is such that the operator can control the extent to which the breast of the heel is scoured by the two bands and the machine operates to scour a heel breast surface rapidly and to a high degree of smoothness in one substantially continuous scouring operation without removal of the heel from the scouring means. In practice it may often be the case that the breast of a heel will be satisfactorily and sufficiently scoured by one steady traverse of the heel downwardly across the scouring bands. It will be obvious that in such case the operator has merely to place the heel in the position aforesaid upon the table 113 and simultaneously press it against the scouring bands and downwardly so that the scouring operation is very quickly and easily performed.

In order to prevent any tendency of a heel being scoured being carried off the table in the direction of movement of the scouring bands, the table 113 has a stop 173 secured thereto by means of a screw 175. The stop 173 contacts with the side surface of a heel being scoured and prevents the heel being carried off the table by the action 20 of the moving scouring bands.

Having thus described our invention, what we claim as new and desire to secure by Letters Patent of the United States is:

1. A machine for scouring shoe parts and similar articles comprising a driven roll having a plurality of abrading elements of different degrees of coarseness and fineness arranged in side-by-side relation, according to their respective degrees of coarseness and fineness, along the length of the roll, a work rest, means for guiding said work rest for movement in a path substantially parallel to the axis of said roll, and means tending to maintain said work rest in a position convenient for the presentation of work to the coarsest of said abrading elements, said maintaining means being constructed and arranged to yield to enable said work rest to be shifted to a position convenient for the presentation of the work to a relatively finer abrading element.

2. A machine for scouring shoe parts and similar articles comprising a plurality of driven abrading elements of different degrees of coarseness and fineness respectively, a movably supported work rest, a stop for limiting the movement of said work rest in one direction, said stop serving to determine a position of said work rest convenient for the presentation of work to a relatively coarse abrading element, and a spring for urging said work rest to the position determined by said stop, 40 said spring being yieldable to enable said work rest to be shifted to a position convenient for the presentation of the work to a relatively finer abrading element.

3. A machine for scouring shoe parts and similar articles comprising rotary scouring means having a substantially vertical axis and having relatively coarse and fine abrading elements disposed at higher and lower levels respectively, a work rest constructed and arranged for substantially vertical movement, and means tending normally to maintain said work rest in a position convenient for the presentation of work to the upper relatively coarse abrading element, said maintaining means being yieldable to enable the work rest to be depressed to a position convenient for the presentation of the work to a relatively finer abrading element at a lower level.

4. A machine for scouring shoe parts and similar articles, comprising two abrasive belts of dif-

ferent degrees of coarseness and fineness respectively, a common roll supporting and backing said belts, a pair of rolls cooperating with said common roll to support said abrasive belts respectively, and supporting means for said pair of rolls constructed and arranged for angular adjustment of the axis of each roll of said pair independently of the other roll of said pair, and relatively to the axis of said common roll, whereby the position of each of said belts on the surface of said common roll may be determined.

5. A machine for scouring shoe parts and similar articles comprising a roll having its axis disposed substantially vertically, an abrasive belt of relatively coarse grit looped about said roll, an abrasive belt of relatively fine grit looped about

said roll below the first mentioned belt, means for supporting the opposite ends respectively of the loops formed by said abrasive belts, a work rest constructed and arranged for substantially vertical movement, and means tending normally to maintain said work rest in a position convenient for the presentation of work to that locality of the upper relatively coarse abrasive belt which is backed by said roll, said maintaining means being yieldable under pressure to enable the work rest to be depressed to a position convenient for the presentation of the work to that locality of the lower relatively fine abrasive belt which is backed by said roll.

JOSEPH GOULBOURN.

WILLIAM RODERICK BARCLAY.
